US0D1086911S

(12) **United States Design Patent** (10) Patent No.: **US D1,086,911 S**
(45) Date of Patent: ** Aug. 5, 2025

(54) **SECURITY SENSOR**

- (71) Applicant: **Amazon Technologies, Inc.**, Seattle, WA (US)
- (72) Inventors: **Wen-Yo Lu**, Pasadena, CA (US); **Alexsandra M. Bowers**, Fairview Park, OH (US); **Stephen James Grant**, Woodinville, WA (US); **Christopher Loew**, Palo Alto, CA (US); **Vinay Sao**, Malvern, PA (US); **James Siminoff**, Pacific Palisades, CA (US); **Yen-Chi Tsai**, New Taipei (TW)
- (73) Assignee: **Amazon Technologies, Inc.**, Seattle, WA (US)
- (**) Term: **15 Years**
- (21) Appl. No.: **29/952,075**
- (22) Filed: **Jul. 12, 2024**

Related U.S. Application Data

- (63) Continuation of application No. 29/821,890, filed on Jan. 4, 2022, now Pat. No. Des. 1,035,472.

(57) **CLAIM**

The ornamental design for a security sensor, as shown and described.

DESCRIPTION

FIG. 1 is a top perspective view of a security sensor;
FIG. 2 is a back perspective view thereof;
FIG. 3 is a left-side view thereof;
FIG. 4 is a right-side view thereof;
FIG. 5 is a bottom view thereof;
FIG. 6 is a top view thereof;
FIG. 7 is a front view thereof; and,
FIG. 8 is a back view thereof.

The dashed broken lines depict portions of the security sensor that form no part of the claimed design. The dot-dashed broken lines represent boundaries of the claimed security sensor and form no part of the claimed design.

1 Claim, 8 Drawing Sheets
